PROCESS OF PREPARING PYRIDYL-MERCURIC SALTS

Randolph Norris Shreve, West Lafayette, Ind., and Maxwell James Skeeters, Pittsburgh, Pa., assignors to Mallinckrodt Chemical Works, St. Louis, Mo., a corporation of Missouri

Application June 16, 1938, Serial No. 214,060

2 Claims. (Cl. 260—270)

This invention relates to processes of mercuring pyridine, and, with regard to certain more specific features, to processes of preparing pyridylmercuric salts.

5 Among the several objects of the invention may be noted the provision of an economical process of preparing pyridylmercuric salts from commonly available, economical raw materials, with relatively high yields of such salts in any desired condition of purity. Other objects will be in part obvious and in part pointed out hereinafter.

The invention accordingly comprises the steps and sequence of steps, and features of procedure, which will be exemplified in the processes herein-
5 after described, and the scope of the application of which will be indicated in the following claims.

Figures 1, 2, and 3 of the accompanying drawings are graphs illustrating certain relationships hereinafter to be explained.

0 The mercuration of pyridine with mercuric acetate has heretofore been described by McCleland and Wilson in the Journal of the Chemical Society, London, 1932, part I, pages 1263—1265. The McCleland and Wilson procedure was to heat 5 mercuric acetate (1000 g.) with pyridine (200 c. c.) in an autoclave at 180° C. for 2 hours, then to filter off the insoluble residue, dilute the filtrate, and precipitate the pyridylmercuric chloride from the filtrate by adding an excess of sodium chloride solution.

While this process operates in the manner stated by the authors, its yields are so meagre that it is practically a prohibitively expensive method. We have repeated the McCleland and Wilson process many times, and have not at any time been able to obtain a yield of pure pyridylmercuric chloride of greater than about 7% of the theoretical yield, based upon the amount of mercuric acetate used. In their article, McCleland and Wilson indicate a 27.55% yield of crude pyridylmercuric chloride, and a yield of 6.89% of pure pyridylmercuric chloride, on the same basis, but we have been unable to obtain any such yields of crude material following the directions of McCleland and Wilson.

One of the principal objects of the present invention, therefore, was to determine, if possible, what factors were operating to reduce the yield of the McCleland-Wilson process to so low a value, and then to determine the proper conditions for bettering such yields. This we have succeeded in doing, as explained in detail hereinafter, and our process, consequently, brings about commercially entirely practicable yields.

A first approach to the problem of low yields was made along the line that the insoluble residue formed in the McCleland-Wilson process was itself suppressing the yield of the desired pyridylmercuric salt. Investigation of this insoluble residue shows that it is probably a mixture of highly

complex polymermercurated pyridine compounds, corresponding to formulae such as

5

or

10

or

15

or

20

The presence of such complex compounds would certainly reduce the yield of the desired pyridylmercuric salts, because of their consumption of large amounts of the available mercury.

A first aim of our work, therefore, was to eliminate or at least reduce the formation of this insoluble residue.

Earlier work seemed to indicate that, in the mercuration reaction, no coupling of the mercury to the pyridine took place until after the commencement of the formation of the insoluble residue. However, further experimentation revealed that this was not the case, and that, in all probability, a major portion of the insoluble residue was formed by reaction of the already-formed pyridylmercuric acetate with further pyridine and mercuric acetate. We accordingly tried an experiment in which the heating of the reaction mixture was discontinued immediately upon the commencement of the formation of the insoluble residue. For example, in a reaction mixture consisting of 25 grams of mercuric acetate and 50 c. c. of pyridine (the proportions used by McCleland and Wilson), heated at 180° C. in an autoclave, the insoluble residue commenced to form in about 32 minutes, and the yield of crude pyridylmercuric chloride, stopping the reaction after 32 minutes, was 18.5%, against the 7% yield following the directions of McCleland and Wilson.

Prolonging the heating period beyond 32 minutes results in the formation of ever-increasing amounts of insoluble residue, and in ever-decreasing yields of pyridylmercuric chloride.

It is accordingly a first feature of our process to discontinue the heating of the reaction mix-

30

45

50

55

60

ture, and hence to discontinue the reaction, substantially immediately upon the formation therein of any insoluble residue.

While the yield is thus improved, it is still not entirely satisfactory. We accordingly undertook next a series of experiments to determine the effect of varying reaction temperatures upon the yields.

Numerous batches of reaction mixture were made up, each comprising 15 grams of mercuric acetate and 30 c. c. of pyridine. These were heated at various temperatures for various lengths of time in an all-glass autoclave, so that the point of the commencement of the formation of the insoluble residue could be noted. The reaction mixtures were then treated to recover crude pyridylmercuric chloride by a procedure hereinafter to be described, and the yields calculated. The results are plotted in graph form in Fig. 1. Three curves are shown, one each for reaction temperatures of 180°, 170°, and 160°. On each curve, an "x" indicates the time at which the formation of insoluble residues commenced. It will be noted that the maximum yield in each instance occurs at the "x" point, offering further confirmation of the aforementioned first feature of the invention.

The maximum yield, it will be noted, increases as the temperature of the reaction is decreased. However, attempts to repeat the experiments at temperatures below 160° (at 155°, for example) resulted in no appreciable mercuration of the pyridine.

A second feature of the invention accordingly comprises carrying out the reaction at the lowest temperature at which it will proceed (160° in the case of a simple mixture of pyridine and mercuric acetate). Thus is the yield of pyridylmercuric chloride somewhat higher.

Attempts were made to increase the yield of pyridylmercuric chloride by varying the proportions of the reactants. In general such attempts showed that the ratio we had been using was an optimum ratio, for while an increased dilution with pyridine increased the yields of pyridylmercuric chloride slightly, it also caused the undesirable formation during the reaction of mercuric oxide, and an increased concentration of mercuric acetate in the reaction mixture distinctly depressed the yield.

For further enhancing the yield, we undertook a series of experiments in which we added water to the reaction mixture. For our initial experiments, we used mixtures in which the water was added in equal molecular proportion with the pyridine. The first series of runs were conducted at 170°, 165°, and 160°, the temperatures found most satisfactory in the previous study of the effect of temperature upon the reaction. The results are plotted as appropriately-indicated curves in Fig. 2. Again "x" indicates the point at which the formation of insoluble residue commences, and this point, it will be noted, approximately coincides with the point of maximum yield, as heretofore.

With the added water, however, it becomes possible satisfactorily to carry out the reaction at temperatures below 160°, and the curves corresponding to such temperatures (155°, 150°, and 140°) are shown in Fig. 2. It will at once be noted that the 155° curve shows a maximum yield (just under 50%) that is by far the highest yield yet obtained in the reaction, and that this yield is considerably greater even than the maximum yields of the nearest-adjacent temperatures (150°

and 160°). It therefore appears that 155°, or close to this temperature, is the particular optimum temperature, under the given conditions, to carry out the reaction.

It is not entirely clear as to just why the water increases the yield so markedly, but it is probably because the water tends to retard the formation of the highly complex polymercurred pyridines, thus making more of the mercuric salt available for the desired monomercuration.

It will be noted that one effect of the addition of water is to prolong the duration of the reaction prior to the appearance of insoluble residues, which is also the approximate point of maximum yields. This fact tends to support the retardation theory of the preceding paragraph. The prolongation, however, is not serious from the standpoint of cost, as but 2½ hours are needed to obtain maximum yield at optimum temperature (155°).

Still another series of experiments was run to determine the optimum amount of water for the reaction mixture. In these experiments, the amounts of pyridine and mercuric acetate in the reaction mixture were held constant, but the amount of water (in molar ratio to the mercuric acetate) was varied. All reactions were carried out at 155°, and were stopped after 2½ hours. The yield of each experiment was determined, and the results plotted as the curve of Fig. 3. It will at once be seen that a water-to-mercuric acetate molar ratio of about 8 is productive of maximum yields. This is the same as the equimolar ratio of water to pyridine as used in the preceding series of experiments.

From all of the foregoing, it will be seen that we have established, as the several criteria for optimum yield of pyridylmercuric chloride, the following:

(1) The reaction mixture should be made up of equimolar parts of pyridine and water, and a portion of mercuric acetate sufficient to make the water (or pyridine) to mercuric acetate molar ratio equal to about 8.

(2) The reaction should be carried out at close to 155°.

(3) The reaction should be continued only until the formation of an insoluble residue commences, that is, about 2½ hours.

An incident to the stoppage of the reaction at the time that the insoluble residue commences to form is that the resultant reaction mixture will contain unreacted mercuric acetate. This unreacted mercuric acetate makes it impracticable to follow the chloride treatment procedure as advocated by McCleland and Wilson, because the chloride solution will precipitate mercuric chloride as an undesirable contaminant in the precipitated pyridyl-mercuric chloride. A better procedure, which was used in substantially all of the foregoing experiments, and which removes the unreacted mercuric acetate prior to the precipitation of the pyridylmercuric chloride, is as follows:

After the reaction has been carried out in the autoclave for the desired time, the residue is filtered off from the reaction mixture. The filtrate is then transferred to a vacuum still, where about two-thirds of the excess pyridine is distilled off at as high a vacuum as conveniently possible (say, 730 m. m. of mercury). The residue may advantageously be washed with water in the meanwhile, and the wash water used to wash the residue (a viscous syrup) from the still. The solution is then diluted with water, and an excess of a caustic solution (such as sodium or potassium

hydroxide) is added with strong agitation. The caustic brings about the precipitation of the unreacted mercuric acetate, residual tars, and to some extent any lower polymercurated pyridine compounds present by reason of their solubility in pyridine. After allowing the precipitate to settle out, it is filtered off, and the filtrate is desirably clarified with decolorizing carbon. Then the filtrate is brought back to its original acidity and diluted again with water. Sodium chloride solution is then added, preferably dropwise and with constant agitation, until it is in excess. This causes the precipitation of crude pyridylmercuric chloride, which is preferably allowed to settle for 18 to 24 hours prior to filtering it off. The product is then dried at 125°, and it may be purified by recrystallization if necessary.

If other salt solutions, such as sodium nitrate, are used in place of the sodium chloride, the products are correspondingly other pyridylmercuric salts, such as the nitrate, or if the clarified filtrate is evaporated and crystallized out without the addition of any salt, the product is pyridylmercuric acetate.

With the foregoing criteria in mind, we have worked up a preferred manner of carrying out the process of the present invention, utilizing the various features of the invention as hereinbefore pointed out. This preferred process is as follows:

An autoclave is charged with pyridine (8 mols.), agitation is started, and mercuric acetate (1 mol.) added. Agitation is continued until the mercuric acetate is entirely in solution. Water (8 mols.) is added and the autoclave sealed. Heat is applied, raising the temperature as rapidly as possible to 155° C., where it is held for two and one-half hours. The autoclave is then allowed to cool and contents pumped to a filter. At this point, in plant operation, it may be advisable to add a chloride free filter aid to the charge and/or to precoat the filter, since the first formed insoluble residue is very fine and gummy.

The filtered charge is run to a vacuum still and the press is washed with water, which has previously been used to wash out the autoclave, and the wash sent to the caustic treatment tank.

The charge in the vacuum still is then distilled under high vacuum (730 mm.) until about two-thirds of the excess pyridine is removed. The residue, which is now in the form of a viscous syrup, is washed from the still into the caustic treatment tank. The combined still residue solution and wash water from the autoclave and press is diluted to about ten times its original volume (as charged into autoclave) and caustic soda (1 mol.) in 40% solution, is slowly added, with good agitation. The agitation is continued for one hour after the caustic addition.

At this point there are two likely methods of handling the charge:

(1) Decolorizing carbon may be added directly and the agitated charge filtered at once. (The only objection to this method is slow filtration of the entire charge.)

(2) Agitation may be stopped and the charge allowed to settle for a few hours. The clear liquor above the settled mercuric oxide and lower polymercurated products may be siphoned off. The settled residue is then filtered, the filtrate added to the bulk of the charge and then clarified.

Following either of the above steps, the precipitated residue is dissolved in acetic acid, reprecipitated with caustic, and filtered, following the

procedure above. This step is to free any occluded acetate. The filtrate is combined with the first filtrate and sufficient acetic acid is added to neutralize the caustic. After neutralization, the 3-pyridylmercuric acetate is precipitated as 3-pyridylmercuric chloride by the slow addition of a saturated sodium chloride solution while the solution is thoroughly agitated.

The precipitated charge is then pumped to an unagitated tank where it is allowed to stand for twenty-four hours to complete the precipitation of the chloride.

When precipitation is complete, the charge is filtered and washed. The crude may then be dried at 125° C. or, if desired, may be purified by recrystallizing twice from aqueous pyridine and once from water.

The crude product is purified by successive refluxings and crystallizations from, first, 25% aqueous pyridine; second, 10% aqueous pyridine; 20 and third, distilled water, with decolorization by means of carbon.

In the first crystallizations from the aqueous pyridine solutions the recovery of crystallized product is sometimes low (65%). However, when 25 the mother liquor from the first recrystallizations is used as the solvent for succeeding recrystallizations very good yields are invariably obtained. In the experimental work recoveries of 98.2%, 92.8% and 98.0% on the first, second, and third 30 crystallizations, respectively, were obtained.

As to equipment, it seems advisable to use either a glass lined or some other type of vitreous or enamelled autoclave. Iron, if present, tends to decrease the yields, and brass is corroded by the 35 reaction mixture. A similar consideration applies to the filters and other treating equipment.

In general, the pressures in the autoclave during the reaction are only those set up by the reaction itself. Such pressures generally run about 40 75 pounds per square inch.

In view of the above, it will be seen that the several objects of the invention are achieved and other advantageous results attained.

As many changes could be made in carrying 45 out the above processes without departing from the scope of the invention, it is intended that all matter contained in the above description shall be interpreted as illustrative and not in a limiting sense.

We claim:

1. The process of preparing C-pyridylmercuric salts, which comprises heating pyridine and a mercuric salt together at a temperature above about 140° C., in the presence of water, until the 55 desired C-pyridylmercuric salt is formed, and discontinuing the heating substantially immediately upon the commencement of the formation of an insoluble residue in the reaction mixture, and recovering the desired C-pyridyl- 60 mercuric salt from the reaction mixture.

2. The process of preparing C-pyridylmercuric salts, which comprises heating pyridine and a mercuric salt together in the presence of water, at a temperature of about 155° C., until the 65 desired C-pyridylmercuric salt is formed, and discontinuing the heating substantially immediately upon the commencement of the formation of an insoluble residue in the reaction mixture, and recovering the desired C-pyridylmercuric salt 70 from the reaction mixture.
